United States Patent Office

Des. 226,621
Patented Apr. 3, 1973

226,621

VEHICLE TRACTION BOARD

Louis Bartman, 7227 Horrocks St.,
Philadelphia, Pa. 19149

Filed Dec. 29, 1971, Ser. No. 213,802

Term of patent 14 years

Int. Cl. D12—05, 99
U.S. Cl. D41—1 C

FIG. 1.

FIG. 2.

FIG. 5.

FIG. 3.

FIG. 6.

FIG. 4.

FIG. 1 is a perspective view of a vehicle traction board showing my new design;

FIG. 2 is a top plan view thereof;

FIG. 3 is a bottom plan view thereof;

FIG. 4 is a front elevational view thereof;

FIG. 5 is an elevational view of one side thereof; and

FIG. 6 is an elevational view of the other side.

I claim:

The ornamental design for a vehicle traction board, substantially as shown.
